UNITED STATES PATENT OFFICE.

IGNATIUS RICE, OF NEW YORK, N. Y.

DESIGN FOR A BREASTPIN.

SPECIFICATION forming part of Design No. 15,116, dated July 1, 1884.

Application filed June 5, 1884. Term of patent 7 years.

To all whom it may concern:

Be it known that I, IGNATIUS RICE, of the city, county, and State of New York, have invented a new and original Design for Breastpins and other Articles of Mourning-Jewelry, of which the following is a full, clear, and exact description, reference being had to the accompanying drawing, making part of this specification, which drawing represents a perspective view of a breastpin, which fully shows the nature of my design.

This design relates to an article of mourning-jewelry of that class to which the character and appearance of crape are imparted; and the invention consists of a breastpin or other like article of mourning-jewelry in which the surface of the body is in imitation of crape, while the sides are ribbed.

In the drawing, A represents a breastpin or

other like article of mourning-jewelry in which the surface of the body is produced in imitation of crape *a*, while the sides *b* are ribbed, as shown in the drawing.

Having thus described my design, I claim as new and desire to secure by Letters Patent—

The design for a breastpin or other like article of mourning-jewelry, consisting of a body the surface of which is in imitation of crape, and the sides of which are ribbed, as shown and described.

In testimony that I claim the foregoing as my invention, I have signed it this 3d day of June, 1884.

IGNATIUS RICE.
